UNITED STATES PATENT OFFICE.

JOHN A. KALLBECK, OF SAN FRANCISCO, CALIFORNIA.

FLUID-OPERATED MOTOR.

Application filed April 12, 1927. Serial No. 183,072.

This invention relates primarily to fluid motors particularly the reciprocating piston type and which may be driven by water, steam or other actuating fluid under pressure, and relates particularly to valve, port and channel mechanism for controlling the admission of pressure to the reciprocating piston.

The primary object of the invention is the provision of means in the form of ducts and channels for controlling the admission of pressure alternately to the opposite ends of a reciprocating valve, thereby dispensing with the necessity of the common valve gear for mechanically controlling the reciprocation of the valve.

A further object is to provide a structure which is simple and durable, which when set in operation will continue to operate indefinitely without attention; one which contains but few parts and is not likely to become out of order.

With the above mentioned and other objects in view, the invention consists in the novel construction and combination of parts hereinafter described, illustrated in the accompanying drawings and pointed out in the claim hereto appended; it being understood that various changes in the form, proportion, size and minor details of construction within the scope of the claim may be resorted to without departing from the spirit or sacrificing any of the advantages of the invention.

Referring more particularly to the drawing, forming a part of the present application—

Fig. 1 is a view in top plan of the preferred embodiment of my invention.

Fig. 2 is a vertical, longitudinal sectional view on line 2—2 of Fig. 1.

Fig. 3 is a transverse vertical sectional view on line 3—3 of Fig. 2.

Fig. 4 is a view in perspective of one of the reciprocating valves.

Referring to the drawings in which like characters designate like parts throughout the several views, 1 indicates a piston cylinder in which reciprocates a conventional piston 2 from which extends a rod 3, the latter operating through a stuffing box 4, in one of the end plates 5, the latter closing opposite ends of the cylinder 1. The upper surface of the piston cylinder wall 6 is relatively flat

at 7 and on the same rests the relatively flat base 8 of a valve casing 9, the latter being formed with a valve chamber 10, closed at its ends by members 11, and in which valve chamber is reciprocably mounted a cylindrical valve 12.

Communicating preferably with the longitudinal center of the valve casing 9 is a fluid inlet 13 and also communicating with the valve casing 9 at either side of the fluid inlet 13 are fluid exhaust ports 14 and 14', 65 they being connected by a Y-exhaust 15 leading to a common point. The respective ends of the cylinder 1 are connected with the respective opposite ends of the valve chamber 10, through fluid inlet and exhaust channels 70 16 and 16'. The respective ends of the cylinder 1 are connected with the opposite ends of the valve chamber 10 through the valve operating by-pass connections 17 and 17', leading from the upper cylinder wall 6, and communicating with the interior of the valve chamber 10 through its side wall, as clearly illustrated in Figs. 2 and 3.

Reciprocably mounted within the valve chamber 10 is a cylindrical valve 12 of a length considerably less than that of the valve chamber, as illustrated in Fig. 2, and provided with a circumferentially reduced central portion 19 affording pistons 20 at opposite ends of the valve. The upper surface of the reduced central portion 19 is channeled at 21 affording a fluid pressure inlet, and the channel divides at its opposite end into a pair of discharge ports 22 and 22' opening through the lower surface of the pistons 20 adapted one to register with each of the inlet and exhaust channels 16 and 16' on the reciprocation of the valve in either direction within the chamber 10. A guide pin 23 extends transversely of the chamber 95 10 and engages the upper side edges of the opening 21 for limiting its reciprocation and preventing the valve 12 from axially rotating within its chamber. The valve is provided at opposite ends with longitudinal bores 24 each opening at one end at the valve end at 25, and each opening at their opposite end through the valve side wall at 26 for registering with one of said valve operating by-pass channels on the reciprocation of the valve in either direction. The valve 12 is further provided with compression relief bores 27 each extending longitudinally

inwardly from opposite ends thereof and opening through the valve side wall to alternately register with the respective fluid exhaust ports 14 and 14' as the valve reciprocates from one end of its chamber to the other.

It will be observed that the valve, when reciprocated to its full stroke in either direction within its chamber, connects the end of one fluid inlet and exhaust channel and the end of a corresponding fluid exhaust port and affords communication from the fluid inlet 13 to the interior of the cylinder 1 through the other fluid inlet and exhaust channel. Reciprocably mounted within the end members 11 of the valve casing 9 are suitable independently movable valve starting or positioning plungers 28.

With the inlet 13 connected with a source of fluid supply under pressure, for example, steam, and with the valve 12 in the position indicated in Fig. 2 of the drawing, and the piston 2 at the end of its stroke, as in Fig. 2 of the drawing, the apparatus operates in the following manner:—

The fluid under pressure enters the cylinder 1 through the inlet and exhaust channel 16', forcing the piston to the right in its cylinder, and immediately on the piston 2 uncovering the by-pass connection 17, the fluid pressure passes through the by-pass connection and enters the bore 24 in the left piston of the valve 12, discharging therefrom through the port in piston surface 25, setting up a compression between the left end of the valve and the corresponding end 11 of the valve chamber. This compression causes a rapid reciprocation of the valve 12 to the right in the chamber 10, and the registering of the compression relief bore 27 at the right end of the valve with the fluid exhaust 14 during the rapid movement of the valve to the right in its chamber, relieves the compression formed in the right end of the valve chamber between the valve end and end 11 of the valve chamber. The reciprocation of the valve 12 to the right cuts off the communication between the outlet port 22' and the inlet and exhaust channel 16'; the solid portion of the right end of the piston cuts off communication between the inlet and exhaust channel 16 and the fluid exhaust 14 after which the end 22 of the channel 21 affords a communication between the fluid inlet 13 and the fluid inlet and exhaust channel 16 enabling fluid under pressure to be admitted into the cylinder 1 at the right of the piston 2. The valve 12 in its reciprocation to the right in its chamber 10 uncovers exhaust 14' and inlet and exhaust channel 16' and affords a registering or connection between the exhaust 14' and the inlet and exhaust channel 16', which enables the escape of pressure through said channel and port which may accumulate in

advance of the direction of reciprocation of the piston 2, as the same travels to the left in the cylinder. The movement of the valve 12 to the right in its valve chamber 10 also connects the by-pass channel 17' with the channel 24 in the right end of the valve, but not before the left end of valve 12 has partly opened channel 16', through which the compressed fluid is now in action, reciprocating the valve 12 towards the right. 75

As illustrated and described, the by-pass channels 17' and 17 admit the fluid under pressure only for a short period alternately to opposite ends of valve 12, the expansive pressure of the fluid rapidly shifting the valve in its casing. This operation of the valve makes it possible to use a short piston 2, which is desirable in apparatus of this type. As the piston passes over and lies to the left of the by-pass 17', the fluid under pressure which has caused the movement of the piston to the left, is instantly admitted into the by-pass 17' and acts on the right end of the valve to reciprocate the same rapidly to the left in the valve chamber 10, thus the valve operation takes place automatically to alternately admit pressure to opposite sides of the piston 2. 90

Should the piston 2 and valve 12 rest at a point offset from their relatively operating positions, the operator in starting the apparatus may, by actuating the members 28, position the valve 12 in its chamber 10 in its relative operating position with relation to the piston 2. 100

I claim:—

A fluid motor comprising a cylinder, a piston reciprocable therein, a valve chamber provided with a fluid inlet port and a pair of fluid exhaust ports, one at either side of the inlet port, said valve casing being further provided with fluid inlet and exhaust channels connecting the cylinder near its opposite ends with the valve chamber adjacent corresponding ends, a pair of valve operating by-pass channels one connecting one end of the cylinder with the opposite end of the valve chamber, said channels opening into the cylinder between the fluid inlet and exhaust ports and opening into the valve chamber one between the fluid inlet port and each of said exhaust ports, a valve reciprocable within the valve chamber and provided with a channel having a single centrally disposed inlet port and a pair of discharge ports, the former communicating with the fluid inlet port and the latter adapted for alternate registering with the respective valve chamber inlet and exhaust channels, said valve at opposite ends being further provided with longitudinal bores, each opening at one end at the valve end and at their opposite end through the valve side wall for registering with one of said valve operating by-pass channels on the re- 115 120 125 130

ciprocation of the valve in either direction, said valve being further provided with compression relief bores extending longitudinally inwardly from opposite ends thereof and opening through the valve side wall to alternately register with the respective fluid exhaust ports, said valve being of a length

when reciprocating its full stroke in either direction within its chamber to afford a fluid pressure inlet to one side of the piston ¹⁰ and a pressure exhaust from the other side.

In testimony whereof I have signed my name to this specification.

JOHN A. KALLBECK.
